UNITED STATES PATENT OFFICE

169,318

BOTTLE CARRIER

Clifton G. Kelley and Thomas T. Kelley,
Baltimore, Md.

Application November 5, 1952, Serial No. 22,132

Term of patent 14 years

(Cl. D58—26)

To all whom it may concern:

Be it known that we, Clifton G. Kelley and Thomas T. Kelley, citizens of the United States, residing at Baltimore, State of Maryland, have invented a new, original, and ornamental Design for a Bottle Carrier, of which the following is a specification, reference being had to the accompanying drawing, forming a part hereof.

Figure 1 is a perspective view of a bottle carrier, showing our new design.

Figure 2 is a view in front elevation.

Figure 3 is a view looking at one end of the carrier.

Figure 4 is a top plan view.

We claim:

The ornamental design for a bottle carrier, as shown.

CLIFTON G. KELLEY.
THOMAS T. KELLEY.
